(57) CLAIM

The ornamental design for a toothbrush sanitizer, substantially as shown and described.

DESCRIPTION

The present application is related to co-pending U.S. patent application Ser. No. 10/622,788, filed concurrently herewith, incorporated herein by reference.

FIG. 1 is a front, right quarter perspective view of a toothbrush sanitizer showing my new design;

FIG. 2 is a rear, left quarter perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof; and,

FIG. 9 is an additional front, right quarter perspective view thereof.

The broken-line disclosures in the views are understood to represent unclaimed subject matter or environment, which form no part of the claimed design.
